UNITED STATES PATENT OFFICE.

HARRY ROSENTHAL, OF CAMDEN, NEW JERSEY, ASSIGNOR OF ONE-HALF TO J. JACOB BAYLSON, OF PHILADELPHIA, PENNSYLVANIA.

ELECTRIC SAD-IRON.

1,150,968.

Specification of Letters Patent. Patented Aug. 24, 1915.

Application filed December 18, 1912. Serial No. 737,372.

To all whom it may concern:

Be it known that I, HARRY ROSENTHAL, a citizen of the United States, residing at Camden, in the county of Camden and State of New Jersey, have invented certain new and useful Improvements in Electric Sad-Irons, of which the following is a specification.

The object of my invention is to provide a novel, simple and efficient, electrically heated sad iron in which currents of air, heated by a resistance coil may be employed to transfer the heat to different parts of the iron and particularly to the point end thereof.

15 A further object of the invention is to provide a construction in which the heating coil and the lead wires connected thereto may be readily removed from the body of the iron as a unit for repair and for other 20 purposes.

The invention consists in the novel features of construction hereinafter fully described and particularly claimed.

In the accompanying drawings, illustrating my invention, Figure 1, is a side elevation of my improved sad iron. Fig. 2, is a longitudinal, vertical section thereof. Fig. 3, is a horizontal section, on line 3—3 of Fig. 2. Fig. 4, is a transverse section, on line 4—4 of Fig. 2.

Referring to the drawings, 5 designates the body of the iron and 6 a handle suitably secured to the top of the body 5. The body portion 5 is made hollow, as shown, and is 35 provided with openings 7 in the upper portions of its sides to permit air to pass into and from the body 5 for a purpose herein-after explained.

Located within the hollow body 5 is a 40 block 8 comprising a horizontal portion 9, extending well into the hollow body 5, and a vertical end portion 10 which is fitted to and closes an opening 11 in the rear end wall of the body. The block 8 is held in place by 45 a suitable set screw 12, screwed into and through the top of the body 5 and engaging the top of the end portion 10 of the block.

The horizontal portion 9 of the block 8 is made hollow, its top being closed by a top 50 wall 13, its sides being closed by side walls 14 and its rear end being closed by the portion 10, leaving the block open at its bottom and at its forward end, as shown.

Supported within the hollow portion of

the block 8 is a resistance coil 15 which is 55 wound around a suitable core 16. The rear end of the core 16 is provided with projections 17 which are inserted into openings in the rear wall of the block 8; and the body of the core 16 is provided with a removable pin 60 18 which extends horizontally through the core and into openings in the side walls 14 of the block 8. Thus the core 16 is supported within the block 8 by the pin 18 and the projections 17. By removing the pin 18 65 the projections 17 may be readily withdrawn from their openings in the block 9 and the core 16 and its coil 15 removed from the block.

The ends of the coil 15 are connected to 70 suitable binding posts 19 on the end portion 10 of the block 9, and connected to the binding posts 19 are lead wires 20 which extend through an opening 21 in the end portion 10 to the exterior of the iron and form 75 continuations of the ends of the coil 15, the wires 21 being adapted to be connected to any suitable source of supply of electric current.

When electric current is supplied to the 80 coil 15, the heat therefrom heats the air within the hollow body portion 5 and causes the air to circulate therein through various courses and to flow into and from the body portion 5 through the openings 7 therein. 85 Some of the air thus heated passes from within the hollow portion 9 of the block around the bottoms of the side walls 14 thereof and up between the same and the side walls of the body 5 of the iron, but most of the moving air passes from the hollow portion 9 out through the open end, in the direction of the arrow in Fig. 2, and thereby maintains the point end of the iron at a higher temperature than the remaining 90 portions of the iron. The hot air circulating within the body portion 5 quickly heats all parts thereof and distributes the heat over the top portion thereof as well as heating the bottom portion so that if the bottom portion be suddenly chilled, it will quickly 95 recover heat from the heat contained in the top or upper portions thereof.

I claim:

1. In an electric sad iron, a hollow body portion having air inlet and outlet openings therein, and a block provided with a resistance coil and supported within the body

portion in spaced relation to the interior walls thereof, said block covering the top and exposing the bottom of said coil.

2. In an electric sad iron, a hollow body portion having air inlet and outlet openings therein, a hollow block supported within the body portion in spaced relation to the interior walls thereof and having a resistance coil supported therein, said block having a closed top, closed sides, a closed rear end, an open bottom and an opening in its forward end above the bottom of its closed sides.
- 10 3. In an electric sad iron, a hollow body

portion, a hollow block supported therein, a resistance coil within the block and having 15 a core provided with a projection inserted into an opening in the block, and a removable pin extending into openings in the block and in the core.

In testimony whereof I affix my signature 20 in presence of two witnesses.

HARRY ROSENTHAL.
